FOUNDATION GARMENT

Morris M. Scheinberg, New York, N.Y., assignor to De Luxe Girlecraft Co., Inc., New York, N.Y., a corporation of New York

Application November 29, 1957, Serial No. 699,811

4 Claims. (Cl. 128—542)

This invention relates to foundation garments or girdles, and more particularly to garments of this type which are intended for maternity use.

In the past many garments or girdles have been designed for maternity use, having provision by which they may be enlarged from time to time, as by letting out seams or laced connections and the like. While these prior garments have in general proved to be satisfactory, they were somewhat bulky or cumbersome, and involved additional components or pieces, together with adjustable connections, which added appreciably to their cost.

An object of the present invention is to provide a novel and improved maternity-type foundation garment or girdle, which will accommodate itself to the normally expected changes in shape, without requiring loosening or resetting of portions or panels, or refitting in any manner.

Another object of the invention is to provide an improved maternity girdle or foundation garment, which will automatically and continuously compensate or adjust for the increases in size of the wearer.

A still further object of the invention is to provide an improved maternity girdle or foundation garment as above set forth, wherein added support is given to the lower portion of the abdomen of the wearer, as the size becomes larger, thereby to produce an advantageous and beneficial uplight effect.

A feature of the invention resides in the provision of an improved maternity girdle as above set forth, which provides the utmost comfort by virtue of the uplight effect and adjustment for increased size occurring automatically and continuously as time goes on, all without requiring attention on the part of the user.

A further object of the invention is to provide an improved maternity foundation garment having all of the above advantages and which is nevertheless simple in its construction, and extremely economical to fabricate.

Other features and advantages will hereinafter appear.

In the drawings accompanying this specification, similar characters of reference are used wherever possible throughout the several views, in which:

Figure 1 is a front elevational view of an improved maternity girdle or foundation garment made in accordance with the invention.

Fig. 2 is a rear elevational view of the maternity garment.

Fig. 3 is a left side elevational view of the maternity garment of Figs. 1 and 2.

As shown, the improved foundation garment of this invention comprises a tubular, waist-encircling body designated generally by the numeral 10, said body including top and bottom elastic edgings 11 and 12 respectively, which are adapted to encircle the waist and the hips of the wearer. The body 10 further includes a pair of side panels 14 and 15 which are connected together at the back of the body by a centrally disposed, wedge-shaped panel 17 and a pair of smaller, triangular panels 18 and 19.

2

Preferably, the central panel 17 is of one-way stretch material as indicated in Fig. 2, whereas the panels 14, 15, 18 and 19 are of two-way stretch material, also indicated.

Referring now to Figs. 1 and 3, the body 10 also includes a relatively large, front panel 22 which extends from the upper edge or elastic binding 11 of the body to the lower elastic binding 12 thereof.

In accordance with the present invention, the relatively large front panel 22 is made of material which has relatively small resistance to stretching, and in conjunction therewith I provide a pair of reinforcing panels, extending across and spanning the lower portion of the front panel, the entire arrangement being such that the garment will in effect be automatically let out or become larger as required during the period of wear, while at the same time a desirable and advantageous uplight effect is had of the lower portion of the abdomen.

Accordingly, referring to Fig. 1, the front panel 22 is preferably provided with curved or convex side edges 24 and 25, whereby such panel is wider at its center portion than at the upper or lower edge portions thereof, and in conjunction with the panel 22 I provide two overlapping reinforcing panels 27 and 28 which are of material having a much greater resistance to stretch than the material of the front panel 22. Each of the panels 27, 28 is connected with both of the opposite, lower side edges of the front panel 22, and span the lower portion of said front panel. Thus the reinforcing panels 27 and 28 provide appreciable additional support to the lower portion of the front panel 22, which is desirable not only in view of the lesser resistance to stretch which such front panel has, but also to provide an advantageous uplight effect.

As seen in Figs. 1 and 3, the reinforcing panels 27 and 28 have diagonally extending upper edges 30 and 31 respectively, such edges extending from lower points 32 at the side edges of the front panel 22 to higher and opposite points 33 at said side edges. Thus, the said upper edges 30, 31 are seen to cross each other approximately at the center of the front panel 22, and preferably are secured together at this point.

It is seen that each of the panels 27, 28 reinforces the other panel, while both said panels act as a firm reinforcement of the easily-stretched center panel 22.

I have found that, by the provision that the easily stretched center panel in conjunction with the crossing reinforcing panels 27 and 28 the formation garment as shown will automatically let itself out or become larger during the period that it is worn, in accordance with the requirements of the user. Moreover, such action follows wholly from the construction of the garment as above set forth, without requiring attention of adjustment on the part of the user at any time. Additionally, the uppermost, exposed portion of the front panel 22 will let itself out to the greatest extent, whereas the lower reinforcing panels 27 and 28 and the lower portion of the panel 22 will be let out to a lesser extent, and will thereby provide a desirable uplight effect, supporting the lower portion of the abdomen and tending to exert a gentle, upward pressure thereon.

Preferably all of the bottom edges of the panels 27, 28 and 22 are secured together, as by stitching, at the time that the lower elastic edging 12 is applied to the body of the garment.

While, in the illustrated embodiment of the invention, I have shown one particular configuration for each of the front panels 22, 27 and 28, it will be understood that the shapes of these panels may be varied within certain limits without departing from the spirit of the invention. Also, various types of materials may be employed for

the said panels. I have found, however, that an open-mesh material which has substantially a one-way stretch, is advantageous in forming the panel 22, as indicated in Fig. 1, whereas a two-way stretch material is of advantage in forming the panels 27 and 28.

Other variations and modifications may be made within the scope of the claims.

I claim:

1. A foundation garment comprising a permanently tubular waist-encircling body having an upper continuous edge and a lower continuous edge and having a one-piece front panel at its front, extending the full distance from its upper to its lower edge and constituting a relatively large portion of the front of said body, said front panel being adapted for disposition across the abdomen of the wearer and being of material having comparatively little resistance to stretch; and a pair of reinforcing panels of material having greater resistance to stretch, extending substantially horizontally across and in front of the front panel and having diagonally extending upper edges crossing each other, each of said reinforcing panels being permanently connected along substantially its full lower edge with substantially the full lower edge of the front panel and being permanently connected with both of the opposite lower side edges of said front panel and spanning the lower area thereof, thereby to provide additional support to said lower area, a portion of one side of said front panel and spanning the lower area thereof, thereby to provide additional support to said lower area, a portion of one side edge of each one of the reinforcing panels being joined permanently with the entire juxtaposed side edge of the other reinforcing panel, which juxtaposed side edge is coextensive with said portion of one side edge.

2. The invention as defined in claim 1, in which the reinforcing panels constitute substantially half of the area

5

of the said front panel which is of comparatively little resistance to stretch.

3. A foundation garment comprising a permanently tubular waist-encircling body having an upper edge and a lower edge and having a front panel extending from its upper to its lower edge and constituting a relatively large portion of the front of said body, said front panel being adapted for disposition across the abdomen of the wearer and being of material having comparatively little resistance to stretch; and a pair of reinforcing panels of material having greater resistance to stretch, each being permanently connected with both of the opposite lower side edges of said front panel and spanning the lower area thereof, thereby to provide additional support to said lower area, a portion of one side edge of each one of the reinforcing panels being joined permanently with a side edge of the other reinforcing panel which is coextensive with said edge portion, said reinforcing panels having diagonally extending upper edges connected between a lower point on one side of the front panel and an upper point on the other side of the front panel.

4. The invention as defined in claim 1 in which the lower edge of said front panel and both of the said reinforcing panels which are secured together constitute a part of the continuous lower edge of the said body.
